UNITED STATES PATENT OFFICE

PAUL G. ANDRES, OF ST. CHARLES, ILLINOIS, ASSIGNOR, BY MESNE ASSIGNMENTS, TO UNITED REPRODUCERS CORPORATION, OF ST. CHARLES, ILLINOIS, A CORPORATION OF NEW JERSEY; GEORGE CUGLEY AND LESTER E. NOBLE, RECEIVERS OF SAID CORPORATION

SOUND REPRODUCER

Application filed December 18, 1926. Serial No. 155,601.

The present invention relates to sound reproducers or regenerators and the like.

Among the objects of the invention is to provide a novel sound reproducing or regenerating device capable of rendering or emitting sound or sound waves or like vibrations with purer tonal characteristics without loss of overtones and the like over the whole range of audible vibrations than heretofore, and with substantially uniform amplitude and volume of vibration and sound throughout such audible range, thus avoiding the defects of the volume and amplitude tapering off from the point of fundamental frequency or natural period and the tones being rendered flat or with blasting sounds or the like.

To attain the end indicated, the invention comprehends as one of its features the provision of means for setting the vibratory parts at a zero load or neutral position when the vibrator or generator is in non-vibratile or vibrating condition or, in the case of an electro-magnetic device, when the latter is de-energized. In this way the energy of the vibrator is efficiently available for transformation into sound vibrations without an absorption of part thereof in overcoming inertia or the like in the parts to be vibrated owing to improper positioning or balancing thereof, or by reason of the weight of any of the parts such as a vibratable diaphragm, disk or cone or the like. In a specific illustrative embodiment the armature of the electromagnetic generator is brought to normally medial position, when the generator is de-energized, by an adjusting means on the support of the device and connected to a vibratable cone which is connected to the armature.

Another object of the invention is to provide a free vibrating diaphragmatic member with its edge or base margin free so that the same may vibrate in unison with the remainder of the member without any impedance as would be present if the margin or edge portions were held or clamped to or between rings of a support. In this way all parts of the member are free to emit

or initiate sound waves in substantially equal or uniform amplitude or volume.

A further object is to provide the device with a vibratable element, such as a reed or the like made vibrant by connection to an armature of an electro-magnetic regenerator, the element preferably having a characteristic natural vibration and also a loop point, yet being capable of transmitting all frequencies of vibration, throughout the audible range of frequencies, to the vibratable member, such as the diaphragm or cone, as a load transmitting element. The vibratable member is preferably connected at a loop point of the reed. The natural periods of the cone and the reed are preferably remote so that when vibrations at or near the natural period of the cone is being produced from the regenerator, the reed will act as a load transmitter and the cone will act with efficiency by reason of the vibrations being at or near its characteristic frequency point, and when the vibrations are remote from the fundamental of the cone but proximate to or at the fundamental of the reed, the latter acts efficiently to impose upon the diaphragm full amplitude of vibration as if the vibrations being transmitted were at or near the fundamental of the cone. The reed also has the characteristic of transmitting overtones and the like so that the rendition of sound by the cone will be nearer to the original tones than those heretofore possible.

Other objects, features, capabilities and advantages are comprehended by the invention as will later appear and are inherently possessed thereby.

Referring to the drawings, Fig. 1 is a view partly in vertical section and partly in side elevation of an embodiment constructed in accordance with the invention.

Fig. 2 is a fragmentary front view of the same.

Fig. 3 is a fragmentary part sectional and part elevational view of a variation of adjusting means used in the same, and

Fig. 4 is a part horizontal sectional and plan view of the feature shown in Fig. 3.

Referring now more in detail to the draw.

ings, the embodiment selected to illustrate the invention is shown as comprising a support 1 having a base or pedestal 2 and extending upwardly into the form of an annular supporting part 3, to which may be secured a regenerating unit comprising a base plate 4 suitably secured to the part 3 by means of securing elements 5 such as screws, bolts or the like. The regenerating means 10 is of any desired construction but preferably comprises a permanent magnet 6 having poles 7 and 8 carrying shoes 9 and 10 supporting one or more solenoids 11 having a core space 12 in which may be located a vibratory or oscillatable armature 13 in any suitable manner as upon or against fulcrum points 14.

On the opposite side of the member 3 may be provided a recess 15 forming a shoulder 16 to which may be secured one end of a vibratable element 17, preferably in the form of a reed, as by means of a suitable securing element 18. This reed is preferably of non-magnetic material. The other or free 25 end 19 of this element is preferably connected by a connecting rod or wire 20 which is also connected to an end 21 of the armature 13 whereby when the armature is vibrated the vibration is transmitted through 30 the connecting element 20 to the free end of the element 17, the element 20 passing through a suitable aperture 22 provided in the plate 4 as clearly shown in Fig. 1 of the drawings.

35 The element 17 when vibrated will have an independent vibration of its own and vibrate with greater efficiency and amplitude at a loop point thereof. At this loop point 23 is connected a rod or wire 24 which extends to and is secured to a vibratable member illustrated in the embodiment as in the form of a cone 25, the rod 24 being connected thereto by means of nuts or the like 26 and 27 and light weight aluminum washers 40 28 and 29 as clearly shown in Fig. 1 of the drawings. It is to be understood that any other mode of connection may be adopted without departing from the spirit of the invention, but that illustrated and described 45 is illustrative. The base portion of the cone is shown with a free edge or marginal part 30 which is out of engagement with any part of the support so that the edge portion will have a free vibration and move in 50 unison with the remainder of the cone without impedance or hindrance.

55 If the vibratable member 25 were supported wholly by the rod 24 it will be apparent that the element 17 would swing to the side and hence also swing the armature 13 to one side and the actuation of the cone from the armature and to the element 17 would produce an incorrect emission or rendition of sound from the surface of the cone. 60

65 In order to support the cone in proper

position whereby the armature would be in neutral condition or in normally medial position within the solenoid, and yet be free to vibrate throughout the whole vibrating member including the marginal part 30 70 thereof, a supporting element 31 is secured as by a rivet or the like 32 to a lower part of the marginal portion 30. This element 31 is preferably of thin metal and sufficiently stiff to support the cone 25 in the vertical 75 direction, yet very flexible in a horizontal direction so that the vibration of the marginal portion 30 will not be hindered by this connecting element 31. The lower end of the element 31 may be provided with a 80 head 33 being preferably beveled and adapted to rest upon a supporting element 34 adjustably secured to the support 1 by way of a bolt 35, the latter passing through an elongated slot 36 permitting the location 85 of the bolt in any selected and vertically adjusted position within the slot. The top surface of the member 34 may be serrated or grooved whereby the head 33 may rest in any selected one of the grooves when 90 adjusting the position of the vibrating member 25. In this way the supporting means may be adjusted vertically along the support 1 or the cone adjusted laterally until the armature 13 is in mid position within 95 the solenoid. If the armature be not in such position after vertical adjustment is made, the lower part of the cone 25 may be moved laterally until the armature is so positioned. The head 33 may then be rested in any 100 selected one of the grooves on the member 34.

105 In Figs. 3 and 4 is shown another form of supporting and adjusting means comprising a permanent magnet 37 secured by a bolt 35 in the same manner as the element 34 is secured, so that the permanent magnet may be vertically adjusted to the desired height. The poles 38 and 39 are preferably spanned by the head or element 33 110 which is preferably of magnetic material and adapted to be held to the magnet at any position along the upper surface 40 thereof where the head 33 may have been moved. As the marginal portion 31 vibrates 115 the element 31 will swing laterally therewith and the head 33 will rock as a fulcrum element upon the top surface 40 of the permanent magnet yet remain in place without danger of sliding or moving, by reason of 120 the magnetic attraction between the permanent magnet and the head 33.

125 While I have herein described and upon the drawings shown illustrative embodiments of the invention, it is to be understood that the invention is not limited thereto but comprehends other features, details, arrangements of parts and constructions without departing from the spirit thereof. 130

Having thus disclosed the invention, I
claim:

A sound reproducing device, comprising
a support, a vibratable diaphragmatic
member, means on the support and connected
5 to said member for vibrating said member,
said member having a free edge and being
spaced from said support whereby the mem-
ber may vibrate freely as a whole, a flexible
10 supporting element connected to the lower
edge of said member, a supporting part con-
nected to said support and adapted to sup-
port said element in any selected position on
said part.

In witness whereof, I hereunto subscribe
15 my name to this specification.

PAUL G. ANDRES.
